UNITED STATES PATENT OFFICE.

EDWARD R. HARRIS, OF NEW YORK, N. Y., ASSIGNOR TO JOHN HENRY HARRIS, OF LACHINE, QUEBEC, CANADA.

TALKING-MACHINE RECORD AND PROCESS OF MAKING SAME.

1,413,984.

Specification of Letters Patent. Patented Apr. 25, 1922.

No Drawing.

Application filed October 31, 1919. Serial No. 334,888.

To all whom it may concern:

Be it known that I, EDWARD R. HARRIS, a subject of the King of Great Britain, and resident of borough of Manhattan, in the city of New York, in the county of New York and State of New York, have invented certain new and useful Improvements in Talking-Machine Records and Processes of Making Same, of which the following is a specification.

The object of my invention is the manufacture of a talking machine record, the body of which will be non-thermoplastic, but forming under heat and pressure a solid material which is not liable to warp and is of sufficient strength and hardness to meet all requirements.

In the present invention the objectionable features common to records made of paper or other material filled with a thermoplastic binder are overcome. In records of this class the tendency for the heat and pressure used in forming the record is to force out the thermoplastic filling and leave the paper or fibrous material with insufficient binding material to cause it to adhere and form a solid mass. This adhesion is absolutely necessary to prevent the paper from returning when pressure is released and causing the record to warp, or otherwise distort the configurations thereon. Thus in using the ordinary non-thermoplastic material such as glue or sodium silicate with the usual facing of phonograph stock, I have found that the tendency is for the pressure to crush the filling material, causing it to break up and produce an unmarketable record.

My invention consists in the manufacture of a talking machine record consisting of paper, cardboard or other fibrous material and permeating it with a non-thermoplastic material consisting of a mixture of glue, dextrine and shellac. In the manufacture of such a record I make an aqueous solution of each of the above ingredients and combine it with the paper or other material by mixing it with the pulp or fibre and subsequently forming it into disks or sheets, or by placing sheets or disks of the paper or fibre into a bath consisting of the glue, dextrine and shellac. Other non-thermoplastic gums, glues or binders can be employed to give the characteristics desired to the record.

Ordinary shellac may be used for this purpose and dissolved by heating it in an

alkaline solution such as borax and water in the proportion of about 1 oz. of borax to 12 ozs. of water and about 4 ozs. of shellac. This forms a brown solution when borax is used, dark red with other alkalies. Borax has been found less inclined to thicken the glue which is subsequently added but any alkali can be used and be within the scope of this invention. A solution of glue is now prepared by adding about 6 ozs. of glue to 12 ozs. of water, in which has been dissolved about 4 dr. of borax. I prefer what is known as fish glue for the reason that it is less inclined to become thick and syrupy when the shellac solution is added. When other glues are used this tendency may be overcome by adding a few drops of a weak solution of acetic acid to the shellac solution before mixing with glue. I mix these two solutions stirring while doing so and the resultant is a brown liquid which should be thin and free from all traces of coagulation. I now take dextrine 10 ozs. and dissolve in water 20 ozs. to which has been added $\frac{1}{2}$ oz. of borax and 1 oz. of sugar. This will dissolve more quickly if heated but it must not be boiled or heated above about 150 F. When all the dextrine is dissolved I add this to the previously described shellac and glue mixture while stirring same. The resultant mixture should be thin and liquid and should soak through a piece of dry blotting paper floated upon the surface in about 15 seconds. If necessary to further thin the liquid add water to which borax has been added about 1 dram to 8 ozs. of water. The above compound is particularly adapted for a dipping or impregnating bath and is used by placing therein sheets or discs of paper or other fibrous material and allowing them to remain until thoroughly soaked. When I make the phonograph record from fibre or pulp which has not been made into sheets, such as wood flour, ground fibre, asbestos fibre, or other fibrous materials, I mix the shellac - glue - dextrine compound directly with the fibre and form a thick paste or dough which can be moulded into discs and dried. When this method is used it is not so important that the above compound shall be so carefully made, in fact any alkaline solvent can be used, as a slightly thick or syrupy result mixes about as readily with the fibrous material. The result of either of these methods is a somewhat spongy material which compresses under sufficient pressure.

sure into a compact mass resembling bone in hardness and texture and this result is more satisfactorily accomplished if heat is applied during the operation of pressing. 5 When a small amount of moisture is present due to the water not being all evaporated or the material being in a moist place, the compound becomes somewhat soft or plastic when heated, this property disappearing 10 when thoroughly dried. I now coat the material with ordinary record stock reduced to a powder and apply sufficient heat to cause the powder to adhere, after which it is placed between heated dies and pressed as 15 in the ordinary method of pressing records or in the case of a cheap record the sound grooves may be pressed directly into the material without the above facing of stock the sponginess of the material permitting a fair 20 pressing to be made. While the above proportions are a fair average it is essential to the success of my invention that I am not limited to any special proportions of the mixture ingredients for the following good 25 reasons: Talking machine records are made by pressing the record material between polished metal dies which contain the sound grooves in relief. The material is usually heated until soft and cooled while under 30 pressure. Unless sufficient resistance is offered to the action of the press the material is not brought into absolute contact with the polished surface of the die and an imperfect record results. Also if the material is 35 too hard to accommodate the slight unevenness always present in the dies or material a similar result is attained. One great value of my invention lies in the fact that this property of hardness or softness can be 40 easily controlled. Thus by adding more dextrine an additional hardness or firmness is obtained, a tendency to break or become dry and unmanageable is overcome by adding more glue and an increase in the amount 45 of shellac causes a softness and also prevents the material from being affected by moisture. As all record pressing establishments differ in the amount of heat, pressure, and inaccuracies, present it is an easy matter to definitely find the proportions best 50 suited to the needs of any establishment and make the material accordingly. It is also necessary that I be not limited to any proportions so that I may use different kinds 55 of paper or fibrous material and use the mixture which works best with the one I wish to use or can procure. Another property of my invention which is very valuable is that the material dries with a porous structure as opposed to the closing of the pores or voids which is the result of using a gum or resin. It is necessary that the air displaced by the compression be allowed to escape otherwise blisters result and the record is spoiled. Another important feature 60 is that the liquid dries evenly throughout the porous structure of the fibrous mass and does not concentrate at the surface and edges as is the case with gums, resins, or sizes. This property also assists in preventing the 65 record from warping. I claim also that I may use the ingredients above mentioned separately if necessity arises. I find that sometimes when using a fibrous material such as sulphite pulp, or cheap grades of 70 paper in which either acid or alkali is present the effect of repeated immersions is to cause the liquid to become thick or even to precipitate one of the ingredients and render the bath unfit for further use. I claim 75 the right therefore to use separate solutions and be within the spirit of my invention.

Having described my invention what I claim is:

1. A process of manufacturing talking machine records which consists in combining ingredients of paper pulp or similar fibrous material with glue, dextrine and shellac and pressing the resultant non-thermoplastic material into record form. 80
2. A process of manufacturing talking machine records which consists in permeating a disk of paper or similar material with a mixture of glue, dextrine and shellac and coacting the disk on one or both surfaces 85 with a facing of phonograph stock and pressing the resultant non-thermoplastic mass into record form.
3. A talking machine record consisting of paper or similar materials combined with 100 glue, dextrine and shellac.
4. A talking machine record consisting of paper or similar materials permeated by a non-thermoplastic mixture of glue, dextrine and shellac and coated on one or both surfaces 105 with a facing of phonograph stock.

Signed at New York city, in the county of New York and State of New York, this 30th day of October, A. D. 1919.

EDWARD R. HARRIS.
